POST CAP

Filed Oct. 13, 1930

UNITED STATES PATENT OFFICE

DONALD McDANIEL, OF HAMILTON, OHIO, ASSIGNOR TO THE HAMILTON FOUNDRY
AND MACHINE COMPANY, OF HAMILTON, OHIO, A CORPORATION OF OHIO

POST CAP

Application filed October 13, 1930. Serial No. 488,370.

This invention relates to clamping or connecting members, and one of the objects thereof is to provide such a clamping or connecting member which is simple and rugged 5 in construction, may be readily and yet effectively operated to clamping or connecting position; and is usable, particularly, for connecting a post cap, post signs, or the like, in place.

10 Another object of the invention is the provision of a post cap comprising a few parts of simple construction, which may be easily joined into an assembly, and readily and securely attachable to a post end, for the support of signs and the like.

Another object of the invention is the provision of a post cap incorporating means for attachment to a post end and article supporting means, and a clamping device 20 operable to hold the cap in engagement with the post end and to securely position the article supported thereon.

Other objects and advantages of the invention will be apparent from the following description, the accompanying drawing and the appended claims.

In the drawing, which illustrates preferred embodiments of the invention as applied to a street sign post—

30 Fig. 1 is a side elevational view of a post cap constructed in accordance with this invention;

Fig. 2 is a vertical sectional view taken on the line 2—2 of Fig. 1;

35 Fig. 3 is a plan view of the under side of a cap member;

Fig. 4 is a plan view of the assembled wedging members;

Fig. 5 is a view in perspective of a spacing 40 member; and

Fig. 6 is a vertical sectional view of a post cap showing a somewhat different arrangement of parts.

The drawing, in which like characters of 45 reference designate like parts throughout the several views thereof, illustrates a post cap which is adapted to be readily attached to the end of a post, such as an upright standard in the form of a common pipe. The invention is particularly applicable to the at-

tachment and support of street signs, but is susceptible to other adaptations and uses. The post cap comprises generally an attaching clamp having a cap member 10 which is adapted to be held in clamped engagement 55 upon the end of a post or pipe 11 upon actuation of a wedging means designated generally 12. The wedging means is actuated by tensioning a clamping means which not only provides for clamping engagement of the cap structure with the post end, but also provides for the attachment of one or more articles which are to be supported by the post cap structure. As shown, the clamping means comprises a bolt 14 having a head portion 60 15 which is positioned below the wedging means 12, and which extends upwardly through and beyond the cap member 10, terminating in a threaded end 16 which is engaged by a nut 17. The nut may be provided in any desired form such as the nut of a common machine bolt, or it may be provided in a decorative design such as is illustrated.

The articles to be supported by the post cap 75 are positioned between the cap member 10 and the nut 17 so that upon drawing the nut 17 tight upon the bolt 14 the wedge means are drawn into clamping engagement by tensioning the supported articles so that they are held 80 securely in place. As shown, the cap member 10 is provided with spaced parallel ribs 20 which are symmetrically positioned with respect to the central opening 21 through which the stem of the bolt 14 passes. The ribs 20 85 are preferably spaced with respect to the bolt 14 a distance sufficient to provide clearance spaces between the bolt and each rib for insertion of metal street signs 24; each of which is preferably lettered only on one side so that upon being assembled back to back between the ribs and the bolt each exposed face will have imprinted thereon the desired information.

A spacing member 25 is assembled upon the bolt stem 14 to rest against the top edges of the signs 24 for their further support. The spacing member is preferably an integrally formed casting having a plate portion 26 provided with a clearance hole 27 for the bolt 100

stem. Opposite sides of the face 26 are provided with parallel downwardly extending flanges 28 having inner adjacent faces spaced similarly to that of the ribs 20 so that the 5 flanges 28 will overlie the top edges of the signs 24. Extending from the face 26 in the opposite direction to the flanges 28 are upwardly lugs 30 of substantially the same thickness as the flanges 28, and spaced apart 10 a distance equal to the over-all width of the face 26; that is, the dimension of the face 26 from the outside of one flange 28 to the outside of the opposite flange. Upon assembling the two signs 24 on the cap 10 and then 15 placing a spacing member 25 above them with the flanges extending downwardly a second spacing member 25 is then placed on the bolt 14 at right angles to the first member and with the flanges 28 extending upwardly. 20 Such an assembly results in interlocking of the lugs 30 of the two spacing members so that they are securely held relatively to one another. The second spacing member with the lugs 28 standing upwardly is positioned 25 to receive a second pair of signs 24. Upon inserting the second pair of signs a third spacing member 25 is then assembled to the bolt stem 14 and with its flanges 28 extending downwardly so that they will overlie the upper 30 edges of the signs. If the cap and assembled signs are not to be attached to a post end at the time of assembly the parts may be held in proper relationship by tightening the nut 17 to draw the wedging means against 35 the cap member 10 so that the assembled signs will be retained in place until the time of attachment to the post end. To attach the assembled structure to a post end it is only necessary to loosen the bolt sufficiently to 40 permit the wedging means to telescope the pipe whereupon the bolt is again tightened. The provision of the spaced ribs 20 on the cap member 10 and the similarly spaced flanges on the spacing members 25 securely 45 positions the inserted street signs so that upon assembling the post cap to a post end and drawing the nut 17 up tightly to actuate the wedging means the signs will be securely held against movement by being tensioned 50 between the cap member 10 and the nut 17.

The assembly of street signs to the post cap and the attachment of the cap to the post end is accomplished without the use of attaching means other than provided in the post cap structure alone, and through the medium of a single clamping means which not only serves to hold the signs in assembled relationship but which also actuates the wedging means by which the entire assembly is held 55 in place. The wedging means 12 comprises a pair of members of similar form each having a curved portion of substantially semi-circular cross section, and attached base portions which are adapted to overlie one another. The curved portions of the wedge 60

members have exterior faces which are ribbed to effectively grip the pipe, and interior faces which are tapered similarly to an extension on the cap member which cooperates with the wedge members for attachment of the cap structure to the pipe end. One of the wedge members 32 is provided with a base portion 33 having an opening 34 for the passage of bolt stem 14 and spaced lugs 35 within which the bolt head 15 is received. The lugs 35 are so spaced that the head 15 may be readily received between them but may not turn relatively thereto so that upon drawing the nut 17 tight the bolt and wedging member will be held stationary with respect to one another. The other wedging member 37 is provided with an extending base portion 38 which in assembled position overlies the base portion 33 of the member 32 and is also provided with a clearance hole 39 for passage of the bolt 14. The clearance hole 39 is preferably provided of larger diameter than the hole 34 so that the wedging members may move outwardly into clamping engagement relative to one another while still providing clearance 90 for the bolt stem.

The cap member 10 is provided with a wedging portion which is engaged by the wedging members upon drawing up the bolt to thereby force the wedging members into clamping engagement with the post. As shown, the extension 40 is of sleeve-like form and is positioned concentrically with respect to the bolt opening 21. The exterior face 41 of the wedge extension 40 is conical. A downwardly extending flange 42 is provided on the exterior of the cap member 10 so that upon assembly of the cap member to the pipe end it will overlie the pipe end to provide a finished appearance for the assembly, and may also serve to strengthen the pipe end against strains imposed by the wedging action of members 32 and 37. Flange 42 and sleeve 40 stand concentrically with respect to one another thus providing a ring-like groove 44 within which the end of the pipe 11 is received. Upon tightening the bolt 14 the wedging members 32 and 37 will be expanded outwardly into engagement with the wall of the pipe as they are drawn upwardly on the extension 40.

The clamping action of the bolt tends to force the cap downwardly on the pipe as the wedging means are drawn upwardly so as to bring the groove 44 of the cap into contact with the pipe end. Means are provided on the cap member to engage the pipe end as it approaches this position of contact so that the cap will be held in interfitting engagement and will thus be maintained stationary with respect to the pipe. As shown, spaced wedge ribs 46 are provided at the junction of the outer surface of the sleeve 40 with the groove 44. The ribs 46 each terminate in a sharp edge 47 which is angu- 130

larly related to both the face of the sleeve 40 and the face of the groove 44. These ribs are provided of sufficient size so that as the groove 44 of the cap member is brought 5 into contact with the pipe ends the ribs 46 will be imbedded in the fin 49 on the pipe end which results from cutting off a pipe with an ordinary pipe cutter. To insure contact of the cap groove 44 with the post 10 end and engagement of the ribs 46 upon tightening of this clamp, it may be desirable to aid the downward movement of the cap by tapping the cap with a hammer.

This construction of post cap for attachment 15 of street signs and other articles is quite flexible as to use in that a common bolt may be used in the clamping means and may be readily provided in whatever length is necessary to meet different conditions of installation. For example, if only one pair of 20 signs is to be used, a shorter bolt than the one shown may be provided so that the nut 17 may be tensioned directly against the spacing member 25 on top of this single pair 25 of signs. If the device is to be used at a street intersection other than 90°, spacing members having a proper positioning of the interengaging lugs 30 may be provided for this contingency. If it should be desired 30 to mount three sets of signs, rather than two as illustrated, it is only necessary to provide a bolt 14 of the proper length and the proper quantity of spacing members 25 for the assembly.

35 Referring particularly to Fig. 6, a clamping arrangement is shown which is particularly useful for attachment on solid post ends or on pipe ends that are too small in diameter to receive the wedging means on 40 the interior thereof. A cap member 55 is shown having an opening 21' for passage of a bolt 14', and spaced lugs 20' for positioning signs 24', one of which is shown. The cap 55 is provided with an outwardly flaring skirt 56 having an inner face 57 which is tapered to receive a pair of wedging members 58 and 59. These wedging members, like the wedging members described above, have complementary semi-circular wedging 45 portions and are provided with overlapping base portions; the wedge member 59 having a base portion 60 in which is provided a bolt opening 61 together with spaced lugs 62 whereby the bolt head 15' is held. The base portion 64 of the member 58 is provided 50 with a bolt opening 65 and is positioned above the base portion 60 of the wedging member 59 so that clamping movement of the bolt 14' will be communicated to both 55 wedging members. The sign positioning means are similar to that illustrated in Fig. 1.

60 In attaching the assembled post cap and signs to the post end the wedging means are 65 telescoped upon the pipe end and the nut 17

is then drawn up tight. Where the wedging members are on the interior of the pipe they are expanded outwardly by contact with the tapering face of the skirt 40 to thereby provide a secure clamping engagement with the pipe. Where the wedging members are on 70 the exterior of the pipe, tensioning of the bolt 14' causes the wedge members to be drawn inwardly against the pipe by contact with the tapering face 57 of the cap 75 member.

It will now be apparent that a post cap is provided comprising but few parts of simple construction readily attachable to a pipe end without the necessity of a threaded engagement therewith or the use of set screws. Also, the arrangement of parts is such that a single clamping mechanism serves as a means of attaching the structure to a post 80 end, as well as a means of securely positioning articles such as street signs thereon.

While the forms of apparatus herein described constitute preferred embodiments of the invention, it is to be understood that the invention is not limited to these precise forms 85 of apparatus, and that changes may be made therein without departing from the scope of the invention which is defined in the appended claims.

What is claimed is:

1. In apparatus of the character described, adapted to be attached to a post end or the like, a cap member comprising a cover portion for the post end and a projection telescoping the post end, a wedge member operably associated with the cap member, and means extending through the cap member cover portion and operable upon the cap member for causing said wedge member to grip said post. 95

2. In apparatus of the character described, for use in a sign supporting post cap structure adapted to be attached to a post end; an attaching clamp comprising a cap member having a post end cover portion and a wedging portion, wedge means adapted to cooperate with said cap member for clamping engagement with the post end, and means concentrically related to the cap member cover portion and operable to move the wedge means into clamping engagement between the cap member and the post end. 100

3. In apparatus of the character described, for use in a sign supporting post cap structure adapted to be attached to a post end; an attaching clamp comprising a cap member having a post end cover portion and a wedging portion thereon, wedge means adapted to cooperate with said cap member for clamping engagement with the post end, and clamping means extending concentrically through the cap member cover portion and between the cap member and wedge means, said clamping means being operable to move the wedge means into clamping engagement 110 115 120 125 130

between the cap member and the post end.

4. In apparatus of the character described, for use in a post cap structure adapted to be attached to a post end for supporting a sign; an attaching clamp comprising a cap member having a wedging portion thereon, wedge means adapted to cooperate with said cap member for clamping engagement with the post end, means for supporting a sign on said cap member, and clamping means extending between the sign and wedge means and operable to move the wedge means into clamping engagement between the cap member and the post end.

5. In apparatus of the character described, for use in a post cap structure adapted to be attached to a post end for supporting street signs and like articles; an attaching clamp comprising a cap member having a wedging portion thereon, wedge means adapted to cooperate with the wedging portion of said cap member for clamping engagement with the post end, means for supporting a street sign on said cap member, clamping means, a sign receiving member on said clamping means, said clamping means extending between the sign receiving member and wedge means and operable to clamp the sign between the sign receiving member and cap member while moving the wedge means into clamping engagement between the cap member and the post end.

6. In apparatus of the character described, for use in a post cap structure adapted to be attached to a post end for supporting signs; an attaching clamp comprising a cap member receivable on said post end, said cap member having a wedging portion thereon, gripping means on said cap member adapted to be imbedded in said post end, wedge means adapted to cooperate with said cap member for clamping engagement with the post end, means for supporting a sign on said cap member, and clamping means extending between the sign and wedge means and operable to move the wedge means and gripping means into engagement with the post end.

7. In apparatus of the character described, for use in a post cap structure, an attaching clamp comprising a cap member receivable on a post end, said cap member having a flange extension adapted to overlie said post end and a concentrically positioned wedging portion adapted to extend within said pipe end, wedge means operably associated with the wedging portion of said cap member, and clamp means operable between the cap member and wedge means for causing said wedge means to grip the post.

8. In apparatus of the character described, for use in a post cap structure adapted to be attached to a hollow post end for supporting street signs and like articles; an attaching clamp comprising a cap member receivable on said pipe end, said cap member hav-

ing a flange extension overlying said post end and a concentrically positioned wedging portion extending within said pipe end, wedge means adapted to cooperate with said wedging portion for clamping engagement with the post end, said wedge means comprising complementary members having curved portions receivable between the wedging portion of the cap member and the interior wall of the post and overlapping base portions, and clamping means extending between the cap member and wedge members and operable to move the wedge members into clamping engagement between the cap member and the post end.

9. In apparatus of the character described, for use in a post cap structure adapted to be attached to a post end; an attaching clamp comprising a cap member having a projecting portion receivable on the outside of said post end and a portion forming a cover for the post end, a pair of wedge members movably positioned between the projecting portion of the cap member and the post end, and a clamping bolt extending through said wedge members and the cap member and adapted to move the wedge members into clamping engagement between the cap member and the post end.

10. In apparatus of the character described, for use in a post cap structure adapted to be attached to a post end for supporting street signs and like articles; an attaching clamp comprising a cap member having sign supporting means provided thereon, wedging means adapted to cooperate with said cap member for clamping engagement with the post end, spaced signs, a sign receiving member, clamping means comprising a bolt having a stem portion extending through said wedging means, cap member, and sign receiving member and adapted to be tightened to draw the wedging means into engagement with the cap member, and to tension the signs between the sign receiving member and cap member so that the signs will be maintained in assembled position until such time that the clamp is loosened for attachment to a post end.

11. In apparatus of the character described, adapted to be attached to a post end, or the like, a cap member, wedging means comprising members contacting with the cap member and having overlapping portions with related openings therein, a single member passing through the openings of the members and connecting the wedging means to the cap member, said connecting member being movable to effect clamping between the post end, cap member and wedging means.

12. In apparatus of the character described, adapted to be attached to a post end, or the like, a cap member having a tapering portion telescopically related to the post end, wedging means comprising members contact-

ing with the cap member, each of said members having a semi-cylindrical portion and a transverse extension with an opening therein, a single member passing through the 5 openings of the members and connecting the wedging means to the cap member, said connecting member being movable to effect clamping between the post end, cap member and wedging means.

10 13. In apparatus of the character described, adapted to be attached to a post end, or the like, a cap member, wedging means comprising members having axially related openings, article attaching means comprising 15 14. In apparatus of the character described, a single bolt passing through the openings of the wedging means and the cap member and joining said parts into an assembly attachable to a post cap as a unit.

20 In testimony whereof I hereto affix my signature.

DONALD McDANIEL.
